CLAIM

The ornamental design for a light fitting, as shown and described.

DESCRIPTION

FIG. 1 is a perspective view of a light fitting showing my new design;

FIG. 2 is a top view thereof;

FIG. 3 is a front view thereof;

FIG. 4 is a rear view thereof;

FIG. 5 is a side view thereof; and,

FIG. 6 is another side view thereof.

The broken lines illustrating portions of the light fitting form no part of the claimed design.

1 Claim, 6 Drawing Sheets
